UNITED STATES PATENT OFFICE.

JOHN GATES, OF PORTLAND, OREGON.

STEAM AND HYDRAULIC STEERING APPARATUS.

SPECIFICATION forming part of Letters Patent No. 240,118, dated April 12, 1881.

Application filed October 25, 1880. (No model.)

To all whom it may concern:

Be it known that I, JOHN GATES, of Portland, in the county of Multnomah and State of Oregon, have invented a new and useful 5 Improvement in Steam and Hydraulic Steering Apparatus; and I do hereby declare the following to be a full, clear, and exact description of the same, reference being had to the accompanying drawings, and to the letters of 10 improvement marked thereon.

This invention relates to that class of steering apparatus in which water or other proper fluid is employed to control the movement of a cylinder-piston which actuates, through 15 proper connecting devices, the rudders; and it consists, mainly, in the combination, with a feed-pump and boiler, of a tank, reservoir, or accumulator located between the two, by means of which the boiler-pressure may be employed, 20 if desired, to actuate the cylinder-piston, and also, if desired, a greater pressure may be obtained than exists in the boiler.

It consists, further, in certain details of construction, all of which will be fully described 25 hereinafter.

In the drawings, Figure 1 represents a plan view of a vessel having my improvements applied thereto; Fig. 2, a side elevation of the same; Fig. 3, a sectional elevation of the well 30 enlarged; Fig. 4, a side elevation of the tank and a portion of the boiler with the intermediate pipe system, by means of which the two are united together; Fig. 5, a side elevation of the tank and safety-valve; and Figs. 6, 7, 8, 35 9, 10, 11, and 12, various views of the throttle-valve and its seat.

To enable others skilled in the art to make my improved steering apparatus and properly use the same, I will describe fully its construction 40 and the manner of its operation.

A, Figs. 1, 2, and 3, represents a well of special construction, which may be located at any proper point in the boat above or below the water-line, but preferably so low that water will flow into and fill the same nearly to 45 the top.

a represents a strainer located at the top of the well, and *a'* a pipe extending downward therefrom through the base of the well, which 50 is provided with a cock, *a²*, as shown.

a³ represents an air-pipe extending upward from the well, which is provided with a check-valve opening upward, as shown. If desired, the pipe may be bent upon itself and be extended downward far enough to bring its discharge end beneath the surface of the water, in consequence of which the entrance of air is effectually prevented, even if the valve should leak. 55

a⁴ represents a pipe leading away to the pump, which pipe is provided with any proper check-valve for preventing any backward flow from the pump to the well.

a⁵ represents a pipe extending away to the safety-valve, hereinafter referred to; and *f'*, a 65 pipe, hereinafter referred to, which extends away to the exhaust-pipe of the throttle-valve.

B, Figs. 1 and 2, represents an independent pump, provided with a pipe, *b*, Figs. 1, 2, and 5, leading away to the tank C and entering the 70 same near the bottom, as shown in Fig. 5.

C, Figs. 1, 2, 4, and 5, represents the tank, reservoir, or accumulator; and D, Figs. 1, 2, and 4, the boiler, the tank being located between the pump and the boiler, as shown in 75 Fig. 2.

c represents a safety-valve upon the tank, and *a⁶* the pipe before referred to as extending from the well to the safety-valve.

c' represents a pipe extending from the tank 80 to the boiler. Its point of union with tank is located some distance below the top of the same, for the purpose of forming an air-chamber therein.

c² represents a check-valve, located on the pipe 85 *c'*, the construction of which is such that flow through the pipe from the tank to the boiler is prevented, while flow from the boiler to the tank is permitted.

c³ represents a branch pipe, the ends of which 90 are connected with pipe *c'* upon each side of the check-valve; and *c⁴*, any proper stop-cock, by means of which the flow through the pipe is controlled.

c⁵ represents a check-valve at the boiler, the 95 construction of which is such that flow from the boiler is prevented, while flow into the same is permitted.

c⁶ represents a branch pipe, the ends of which are connected with the pipe *c'* upon each side 100

of the check-valve e^5 , and a stop-cock, e^7 , by means of which the flow through the pipe is controlled.

5 E, Figs. 1, 2, 4, and 5, represents a pipe leading from the bottom of the tank C up to the throttle-valve e , Fig. 2, and from thence to the steering-lever valve-chest e' and the hydraulic cylinder e^2 . The special construction of the throttle-valve and its connections is illustrated 10 in Figs. 6, 7, 8, 9, 10, 11, and 12.

e^3 represents a rod extending downward from the pilot-house, which is provided with a universal joint, consisting of one pin, e^4 , extending through another pin, e^5 , as shown.

15 e^6 , Figs. 6 and 10, represents the valve-rod, which is provided with a threaded end, as shown.

e^7 represents the valve-chest, and e^8 , Figs. 10 and 11, the valve-seat provided with the 20 supply-port e^9 and the exhaust-port e^{10} , as shown.

e^{11} represents the pipe leading from the tank, and e^{12} the pipe leading to the steering-valve chest.

25 e^{13} represents a pipe leading to the exhaust-pipe F.

e^{14} represents the valve, which is provided with proper bearing-faces at its ends and the exhaust-cavity e^{15} , as shown. The operation 30 of this valve will be readily understood. When the valve is fully open the pressure from the main source of pressure will be delivered through the throttle-valve to the steering-valve chest, and from it the same may be applied, as desired, to the pistons of the cylinders by properly actuating the steering-levers. When the valve is closed the pipe e^{12} , connected with the steering-valve chest, communicates with the exhaust-cavity of the valve, 35 and hence the water is permitted to escape for the purpose of relieving the steering-valve chest and cylinders from pressure.

40 F, Figs. 2 and 10, represents the exhaust-pipe, before referred to, which may extend downward through the bottom of the boat, as shown.

f represents a stop-cock, by means of which communication through the lower end of the pipe may be closed, if desired.

45 f' represents the pipe before referred to as extending from the exhaust-pipe to the well.

The operation is substantially as follows: The stop-cock e^4 in the branch pipe e^3 having been closed, and the pump having been put in 50 operation, the water or other liquid in the well may be drawn therefrom and be delivered into the bottom of the tank or reservoir C, from which it is discharged, as it may be needed, through the pipe E, to the throttle-valve and 55 actuating-cylinder, the pipe E leaving the tank near the bottom of the same, as shown. The excess of water thrown by the pump over that taken by the cylinders is delivered from near the top of the tank C, through the pipe e , to the 60 safety-valve, and from thence is forced through the pipe back again to the pump, to be used 65 over again. The water from the pump in this

case, it will be observed, cannot be forced at all into the boiler, the check-valve preventing flow in this direction and the stop-valve e^4 being closed.

70 By properly weighting the safety-valve any desired amount of pressure may be obtained on the tank. When a large amount of water is taken by the cylinders the pressure in the 75 tank is necessarily reduced, and hence the pump will increase the rapidity of its action and throw a greater volume of water, the air-chamber in the top of the tank serving to equalize the delivery in the manner well understood. 80 If, however, the pump should fail to furnish sufficient pressure from any cause—that is, if it should cease to act, or act but feebly—the check-valve e^2 would then be opened by the boiler-pressure and water would be delivered 85 from the boiler to the tank. This hot water, entering the top of the tank through the pipe e , would discharge the water below through the pipe E to the throttle-valve, steering-valve chest, and cylinders. When the pump acts 90 again the hot water received in the tank would be delivered through the safety-valve to the well. Any surplus delivered to the well will be delivered through the strainer a and pipe a' overboard. By means of this relative arrangement of pipes hot water is never delivered to the cylinders.

95 With this construction of parts it is not designed to use the boiler-pressure except in case of accident to the pump, the same serving as a 100 reserve force, which will act only when necessity requires its action. The liquid thrown into the cylinders is discharged through the exhaust-pipe to the well, or overboard, as may be desired.

105 The liquid in the well may be used continuously, if desired, and hence a special liquid may be employed, if desired, such as fresh water when the boiler is using salt-water, or water containing oil or glycerine. In such case 110 the cock a^2 , Fig. 3, is closed, so that water is not admitted from outside, and the exhaust from the cylinders is returned to the well through the pipe f' and the excess from the safety-valve through the pipe a^5 .

115 If desired, instead of employing an independent pump and well, the feed-pump for supplying the boiler may be employed either with the well, as described, or without the well, as shown in Fig. 2^a, in which case substantially the same construction of parts is employed. The cock e^4 in this case, also, is left open, or partially open, so that a proper portion of water thrown by the pump is delivered to the boiler. In this case, also, the water is 125 not used over again, but the excess thrown by the pump is worked off by the safety-valve, and that used by the cylinder is discharged through the exhaust.

130 The cock e^7 is employed for the purpose of closing the boiler in case of a leak in the feed-pipe.

Some of the advantages of the described construction are as follows: By the employ-

ment of tank between the pump and the boiler in the manner described the boiler-pressure is caused to act automatically in case of an accident to the pump. By the employment in connection with a pump of the described arrangements of pipes and valves it is possible to obtain in the tank a greater pressure than exists in the boiler. By the employment of an independent pump the liquid employed may be continuously used. By the use of a throttle-valve, as shown, the steering-cylinders are freed from pressure by simply closing said throttle-valve. If a simple stop-valve were employed, the full pressure would remain in the cylinders when the same was closed.

Having thus fully described my invention, what I claim as new, and desire to secure by Letters Patent, is—

1. In a hydraulic steering apparatus, the combination, with a pump and boiler, of a tank, reservoir, or accumulator located between the two, together with connections, as shown and described.

2. In combination with the tank C and boiler D, the intermediate pipes, $c' c^3 c^6$, and valves c^2 25 c^5 , the construction being such that the pressure of the boiler may be communicated to the tank when desired, substantially as described.

3. In combination with the tank C and boiler D, the intermediate pipes, $c' c^3 c^6$, valves $c^2 c^5$, 30 and cocks c^4 , the construction being such that the pressure in the tank may be made to exceed that in the boiler, substantially as described.

4. In combination with a steering-valve 35 chest and a throttle-valve chest connected by suitable connections, a throttle-valve adapted, when the flow is shut off, to exhaust the former chest, as described.

This specification signed and witnessed this 40
14th day of June, 1880.

JOHN GATES.
